UNITED STATES PATENT OFFICE.

BEAUMONT PARKER, OF HIGHLANDS, KANSAS, ASSIGNOR OF ONE-HALF
TO LEWIS C. PARKER, OF KANSAS CITY, MISSOURI.

GRAIN-MEASURING MACHINE.

SPECIFICATION forming part of Letters Patent No. 392,452, dated November 6, 1888.

Application filed April 17, 1888. Serial No. 270,910. (No model.)

To all whom it may concern:

Be it known that I, BEAUMONT PARKER, a citizen of the United States of America, residing at Highlands, in the county of Don-
5 phan and State of Kansas, have invented cer-
tain new and useful Improvements in Grain-
Measuring Machines, of which the following is
a specification, reference being had therein to
the accompanying drawings.

10 This invention pertains to certain new and useful improvements in grain-measures, having for its object the provision of simple and highly efficient means for measuring grain as the same is emitted from a thrashing-machine
15 and emptying the same automatically after the desired quantity has been secured.

The invention comprises the detail construction, combination, and arrangement of parts, substantially as hereinafter fully set
20 forth, and particularly pointed out in the claims.

In the accompanying drawings, Figure 1 is a central vertical sectional view of my im-
25 proved grain-measure, and Fig. 2 is a horizon-
tal sectional view thereof.

Referring to the drawings, A designates the box or inclosing-casing, in the upper and lower portions of which are formed openings a a', through which the grain is respectively re-
30 ceived and discharged.

B is the measuring can or vessel, divided into two equal-sized compartments, b b', having inclined bottoms b² extending from the central partition-board, b³, to the outer ends of
35 the can or vessel. The top of the measure is open, and the sides are preferably curved at their upper ends.

C is an approximately U-shaped lever-frame fulcrumed near the forward ends of its side
40 arms to the inside of the box or casing A, as at d, and between the outer ends of these side arms is pivotally secured the can or vessel B, the same being held by a cross-rod, d', passed through an aperture in the partition b³. From
45 the rear connecting-bar of this lever-frame C projects an arm, D, whereon is adjustably secured a weight, E.

The can or vessel B is provided with two end-gates, F F', pivotally secured at their upper ends, so as to permit their lower ends to swing outwardly. These end-gates are con-

nected at their side edges by connecting-rods f f', from the centers of which project small rollers f² f², designed to play in vertical slots f³ in the sides of the box or casing, one of said slots being shown in Fig. 1.

To the upper central portion of one side of the can or vessel B is secured a stud or pin of a small roller, g, designed to come in contact with and to be held by hooks G G', attached to
60 the inner side of one of the sides of the box or casing A, said hooks being pivotally secured at their outer ends and held as against too great downward movement by means of pins g' g'.

In practice the can or vessel B always maintains an inclined position, it being so held by the roller g and one of the hooks G G'.

The operation is as follows: Supposing the can or vessel to be in the position shown, grain, 70 on being admitted through the opening a, will fall into the compartment b, the end-gate of which is closed, as shown. Upon the compartment being filled with grain the weight thereof will cause the lowering of the can or vessel as against the action of the weight, the disengagement of the roller g from the hook G, and the movement of said can or vessel on its pivotal cross-rod. This movement of the can or vessel will, through the agency of the connecting-rods f f', cause the opening of the end-gate F' and the closing of the end-gate F, thus permitting the grain to pass from the partition b out through the lower opening a', into the bag or other receptacle placed thereat. 75 While this is being done the grain is passing into the other compartment, b', of the can or vessel, which is held in position by the hook G' and roller g. When the desired quantity of grain has been secured in the compartment b' the weight thereof, causing the depression, will effect the lowering of the can or vessel and the disengagement of the roller g from the hook G', immediately upon which the end-gate F will be opened and the other end-gate 85 closed, so that the compartment b' will again be ready for reception of grain.

The parts are so constructed and arranged that sufficient grain will be passed from one compartment and sufficient received in the other compartment to prevent the roller g moving beyond the inner hooked end of each

hook G G', so that the emptying of the grain in the compartment just filled will cause the can or vessel to move upwardly, and said roller will come in contact with the shoulder of the 5 adjoining hook.

From the foregoing description it will be seen that by means of the weighted lever-frame the can or vessel is normally held elevated, and that upon filling of one of the compartments of 10 said can or vessel the latter will be lowered as against the weight E, and the roller g being freed of the hook, said can or vessel will turn on its pivotal bearing, causing the opening of its end-gate and the discharge of grain therefrom. The can or vessel will then rise to its 15 normal position, causing the roller g to come into engagement with the other hook.

By means of my invention grain is easily, readily, and accurately measured, and the device 20 is extremely simple, cheap, and durable, and embodies advantages in points of simplicity, durability, and general efficiency.

I claim as my invention—

1. The combination, with the box or inclosing-casing having slots in its side walls, of the 25 pivotally-secured can or vessel, the end-gates, and the connecting-rods having rollers working in said slots, substantially as shown and described.

2. The herein-described improved grain-measure, comprising the box or casing having slots in its side walls, the pivotally-secured hooks, the can or vessel having the roller, the lever-frame having a weight secured thereon, the end-gates, and the connecting-rods connected to said end-gates and having rollers working in said slots, substantially as shown and described. 30 35

In testimony whereof I affix my signature in presence of two witnesses.

BEAUMONT PARKER.
